LATCH FOR HOLDING DOORS OPEN

Roland J. Olander, Chicago, Ill., assignor to W. H. Miner, Inc., Chicago, Ill., a corporation of Delaware

Application December 29, 1949, Serial No. 135,698

2 Claims. (Cl. 292—246)

1

This invention relates to improvements in door latches.

One object of the invention is to provide a simple and efficient latch for swinging doors for holding said doors in open position.

Another object of the invention is to provide latch means of the character indicated, especially adapted for hinged doors of refrigerator cars, the latch means being especially designed to be easily operated to release the same when the edge of the door is grasped to swing the same away from the car wall toward closing position.

Other objects of the invention will more clearly appear from the description and claims herein-after following.

In the accompanying drawings forming a part of this specification, Figure 1 is a side elevational view, partly broken away, of a refrigerator car body, having a pair of hinged doors, illustrating my improvements in connection therewith. Figure 2 is a horizontal sectional view, on an enlarged scale, through a portion of the car side wall and a portion of the right hand door shown in Figure 1, with the door swung to fully open position, with the locking bar omitted. Figure 3 is a vertical sectional view, partly broken away, corresponding substantially to the line 3—3 of Figure 2. Figure 4 is an enlarged, elevational view of the pivoted latch element shown at the right hand side of Figure 1 and illustrated in plan in Figure 2. Figure 5 is a top plan view of a modified form of pivoted latch element and hook. Figure 6 is a side elevational view of Figure 5, looking from right to left in said figure, with the hook omitted.

In said drawings, the side wall of the car is indicated by 10, the same having the usual side door opening 11, closed by a pair of hinged doors 12 and 13. The door 12 is closed first and latched in closed position by a well-known type of rotary latch 14, and the door 13 is swung to closed position after the door 12 has been closed and latched, and is then locked in said closed position by the usual locking bar 15, cooperating with keepers 16—16 on the car wall. When the doors are open, they are swung outwardly against the car wall.

In carrying out my invention, I employ a latching mechanism for each door for holding the same in open position, the latch mechanism for the door 13 or the right hand door, as seen in Figure 1, only being shown in the drawings.

Referring first to the embodiment of the invention illustrated in Figures 1 to 4 inclusive, the same comprises broadly a supporting bracket A

2

on the car wall, a pivoted latch element B carried by said bracket, and a keeper element C fixed to the door 13 in cooperative relation with the latch element.

5 The supporting bracket A is in the form of a plate, having an upstanding central tongue 17, provided with an outwardly offset, bowed, or rounded portion 18, forming a bearing member for the pivoted latch element B. The relatively wider bottom section of the bracket A, which section is indicated by 19, is provided with outwardly or forwardly projecting supporting tongues or shelves 20—20 at the upper end of said section 19 at opposite sides of the tongue 17.

10 The bracket A is secured to the outer side of the car wall 10 by rivets 21, extending through the tongue 17 and section 19.

15 The pivoted latch element B is in the form of a loop or ring formed from bar material, preferably of cylindrical cross section. The ring or looplike latch element B has a substantially straight, transverse back section 22 journaled in the rounded bearing member formed by the offset portion 18 of the bracket A. The latch element B is provided with a finger piece 23 at its right hand side, as seen in Figures 2 and 4, by which it may be manipulated, the same being in the form of a short, cylindrical rod welded to the right hand side of the latch element, and extending above and below the latter. As shown most clearly in Figures 2 and 3, downward movement of the latch element B is limited by engagement with the shelves 20—20 of the supporting bracket B and is supported in horizontal position by these shelves.

20 The keeper element C is in the form of a hook fixed to the outer side of the door 13. This element is preferably in the form of a casting, having securing ears 24—24 at opposite sides, and an outwardly projecting, central stem or arm 25. The arm 25 extends horizontally and has an upstanding lug 26 in the form of a tooth at its outer end, which forms the hook proper. The lug 26 has a downwardly inclined, outer edge 27 which forms a cam member for lifting the latch element B when the keeper element is forced against the same as the door 13 is swung open. Inwardly of the lug 26, the keeper element C is provided with a vertically extending web 28, which forms an abutment which is directly engageable with the pivoted element B when the door is swung open to limit opening movement of the door. The keeper element C is fixed to the outer side of the door 13 in alignment with the pivoted latch element B by rivets 29—29 ex-

tending through the ears 24—24 of said keeper element.

As will be evident, when the door 13 is swung open, the keeper element C is forced against the pivoted latch element B, camming the same upwardly until it passes over the lug 26 and drops behind the same, thereby latching the door in open position. To swing the door 13 from the fully open position to close the same, the operator grasps the edge of the door and at the same time manipulates the pivoted latch element B to swing the same out of engagement with the keeper element C. This can be accomplished by use of one hand alone, as the pivoted latch element is located closely adjacent the edge of the door, so that the finger piece 23 thereof may be pulled outwardly away from the car wall to swing the latch element upwardly by pressure of a finger thereon at the same time that the edge of the door is grasped.

Referring to the embodiment of the invention illustrated in Figures 5 and 6, a latch element D and a keeper element E are shown, the keeper element E being identical with the keeper element C hereinbefore described, and the latch element D being similar to the latch element B hereinbefore described, with the exception that the finger piece of the latch element D, which finger piece is indicated by 123 and corresponds to the finger piece 23 hereinbefore described, is formed in one piece with the ring portion of the latch element, the finger piece being in the form of upwardly and downwardly bent end sections of the bar from which the element D is formed, which end sections are welded together, as indicated at 124, to close the ring portion of the element D.

I claim:

1. In a door latch, the combination with a fixed supporting bracket; of a horizontal shelf on said bracket; a pivoted loop element journaled in said bracket for swinging movement about a horizontal axis, said loop element having its downward swinging movement limited to a horizontal position by engagement with said shelf; and a finger piece secured to one side of said loop element, said finger piece extending above and below said loop element at right angles to the length of the same.

2. In a door latch, the combination with a fixed supporting bracket secured to one of said members; of a horizontal shelf on said bracket; a pivoted loop element journaled in said bracket, said loop element being formed of bar material of cylindrical cross section, said loop element being journaled in said bracket for swinging movement about a horizontal axis, and having its downward swinging movement limited to a horizontal position by engagement with said shelf; and a finger piece integral with said loop element, said finger piece extending at right angles to the length of said loop element and projecting above and below the same.

ROLAND J. OLANDER.
